UNITED STATES PATENT OFFICE.

BYRON E. CHOLLAR, OF ST. LOUIS, MISSOURI.

DESIGN FOR A GAS-PURIFIER.

SPECIFICATION forming part of Design No. 31,754, dated October 31, 1899.

Application filed September 2, 1899. Serial No. 729,390. Term of patent 7 years.

To all whom it may concern:

Be it known that I, BYRON E. CHOLLAR, a citizen of the United States, and a resident of the city of St. Louis, in the State of Missouri, 5 have invented and produced a new and original Design for a Gas-Purifier, of which the following is a specification, reference being had to the accompanying drawings, forming part hereof, and in which—

10 Figures 1, 2, and 3 are respectively a plan, a side view, and an end view of my new design.

As shown in the drawings, the leading or material features of my design consist of a 15 pair of centrally-disposed bodies with rectangular bases and cylindrical upper portions, flanged projections extending from the four sides of the rectangular bases, those on adjacent sides of said bases being in contact, 20 longitudinal parts of circular section extend-

ing from the flanged projections on the sides of the bases opposite to the adjacent sides, and two lateral members of circular section, respectively, extending from the ends of the longitudinal projections laterally, thence perpendicularly to the plane of the bases, thence parallel to the plane of the bases, thence back into the plane of the bases, and thence laterally to the longitudinal projections at points intermediate of their ends. 25

Having thus described my invention, what I claim as new therein, and desire to secure by Design Letters Patent, is—

The design for a gas-purifier as herein shown and described.

BYRON E. CHOLLAR.

In presence of—

E. S. KNIGHT,
M. P. SMITH.
